(57)

CLAIM

The ornamental design for a vaporizer device, as shown and described.

DESCRIPTION

FIG. 1 is a bottom, front, and right side perspective view of a vaporizer device of our design;
FIG. 2 is a top, rear, and right side perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The dash-dash broken lines illustrate portions of the vaporizer device that form no part of the claimed design.
The dash-dot broken lines illustrate boundary lines that form no part of the claimed design. The areas within the dash-dot broken lines form no part of the claimed design.

1 Claim, 5 Drawing Sheets
